UNITED STATES PATENT OFFICE.

ERNEST N. HUMPHREY, OF NEW BRITAIN, CONNECTICUT, ASSIGNOR TO UNITED STATES FASTENER COMPANY, OF BOSTON, MASSACHUSETTS, A CORPORATION OF MAINE.

SNAP-FASTENER.

1,094,333.

Specification of Letters Patent. Patented Apr. 21, 1914.

Application filed April 28, 1913. Serial No. 763,961.

To all whom it may concern:

Be it known that I, ERNEST N. HUMPHREY, a citizen of the United States, and resident of New Britain, in the county of 5 Hartford and State of Connecticut, have invented new and useful Improvements in Snap-Fasteners, of which the following is a specification.

My invention relates to fasteners, and 10 more particularly to snap fasteners of the type having a socket member provided with resilient fingers adapted to pass through the material and thereafter to be turned over into holding contact with the material (or 15 with a washer) and to form an annular resilient stud-holding edge or rim adapted yieldingly to hold a solid stud.

The object of my invention is to provide 20 a socket member of this general type where- in effective provision is made for anchor- 25 ing the socket member to the material and preventing its rotation. As is well known to persons familiar with the snap fastener art, rotation of the socket member in these fasteners is very detrimental; first, because 30 it tends to loosen and weaken the fastener and to prevent easy insertion and dislodg- 35 ment of the stud as the parts wear and loosen in use; and second, because the cap of the fastener is usually provided with 40 ornamentation, such as a monogram or other trade mark, and it is commercially essential that such ornamentation shall always be in its proper upright position. While this latter consideration may appear unimpor- 45 tant to persons unfamiliar with the trade, yet commercially it is of great importance; for the manufacturers of gloves, suspenders, etc., who are among the largest users of snap 50 fasteners, insist upon fasteners having non-rotatable caps upon which their trade marks will always be properly displayed so that the goods may be readily recognized as their product.

45 Referring to the drawings which illustrate an embodiment of my invention,—Fig- ures 1 and 2 are respectively a side eleva- 55 tion and a sectional view of my improved socket member; Figs. 3 and 4 are similar views taken on a plane at right angles to 60 Figs. 1 and 2 respectively; Fig. 5 is a bottom view of my improved socket member; Fig. 6 is a sectional view of my improved

socket member attached to material; Fig. 7 is a similar view taken on a plane at right angles to Fig. 6; and Fig. 8 is a side elevation of a stud suitable for use with my im- 65 proved socket member.

The socket member is preferably made of 70 a single piece of metal, cut, stamped and shaped by suitable tools or instruments into the form shown in the drawings. It con- 75 sists essentially of a cap A provided with a plurality of projecting, resilient fingers or arms A' having spurs or barbs A² located therebetween. Preferably the fingers or arms A' are pointed and pressed inward at or near their free ends to permit them readily to pass through a relatively small 80 opening in the material.

In securing the socket member to the material, the fingers or arms A' are passed 85 downward through a suitable hole in the material, and preferably through a washer B disposed on its opposite side. Then by 90 the use of suitable tools the socket member and washer are brought together with the material therebetween and the free ends of the fingers or arms A' are turned over into holding contact with the washer, thus form- 95 ing a resilient stud-holding rim or edge and firmly attaching the member to the mate- 100 rial. It will be apparent that when the socket member and washer are thus brought together upon the material, the barbs or spurs A² enter the latter and anchor the socket member, preventing its rotation at all times and particularly as the turned-over edges of the fingers A' wear and loosen in use.

I claim:—

A socket member of a snap fastener pair, comprising a cap provided with resilient arms adapted to be bent over to form a re- 95 silient, stud-holding rim and to secure said member to the material, and barbs located between said arms adapted to enter the material to prevent rotation of said socket member.

Signed by me at New Britain, Connecticut, 100 this 16th day of April 1913.

ERNEST N. HUMPHREY.
